AIRPLANE CONSTRUCTION

Fritz Freytag, Dessau, Germany; vested in the
Alien Property CustodianApplication September 8, 1939, Serial No. 293,985
In Germany September 10, 1938

5 Claims. (Cl. 244—118)

This invention relates to improvements in airplane construction, and refers particularly to the construction of airplanes intended to transport heavy loads.

Airplanes have already been made wherein doorways were provided in the floors of the central portions of the fuselages through which loading was done, and wherein the doors when open formed ramps extending down to the ground. Such an arrangement, however, is open to the objection that the central portion of the fuselage on which a large portion of the load might otherwise be deposited is displaced, and therefore not available, while loading. Another known arrangement, possible only in airplanes wherein the propelling mechanism is not located in the front portion, or nose, of the fuselage, is to hinge this entire front portion so that it may be swung downwardly to form a loading ladder. This arrangement while permitting utilization of substantially the entire floor space is not well suited for loading heavy goods for the reason that the greater height of this end of the fuselage above the ground involves more lifting of the goods being loaded or the use of longer and steeper ramps. Such an arrangement is also open to the objection that loading from the front might cause the airplane to tip over if too great a weight were accumulated towards the front during the loading or unloading operation; and further this construction presents many difficulties in designing a satisfactory pilot's cabin.

It is an object of this invention to provide an airplane construction wherein the entire usable floor space of the fuselage is made available for loading; and wherein the doorway is so positioned that the floorspace immediately adjacent thereto is positioned quite close to the ground thereby affording maximum stability, and making loading and unloading both simple and safe.

Another object of the invention is to provide such an airplane construction wherein the upper and lower portions of the rear extremity of the fuselage are movable and together function as a door, so that when moved to open position ready ingress and egress are afforded across the entire width of the fuselage.

A further object of the invention is to provide such an airplane construction wherein the movable rear upper and lower fuselage portions are constructed as a single unit, and are hingedly connected to the rear upper extremity of the fixed portion of the fuselage, so that accessories

and smaller articles may be suitably secured to the said walls of the hinged portion and the limited space therein usefully occupied.

Yet another object of the invention is to provide such an airplane construction wherein strong, rigid extensions of the fuselage sides project rearwardly beyond the movable upper and lower walls which constitute the door; and the fuselage sides and their extensions are so constructed and reinforced that the latter, which are preferably elevated towards their rear extremities, support the rear controls, such as rudders and the like, above and clear of the said door throughout its movement.

Having thus enumerated some of the major objects and advantages of the invention, I will now proceed to describe an embodiment thereof with the aid of the accompanying drawings, in which:

15 20 Figure 1 is a plan view of an airplane equipped with my invention, and

Figure 2 is a side elevation thereof showing the loading door in open position.

Figure 3 shows the retractable tail wheels and 25 the hinged ramp in a greater scale.

Within the fuselage 1 a storage space for goods, such as the trucks indicated at 1a is provided. The rear extremities of the upper and lower wall portions of the fuselage, which in the present 30 instance are formed integral, together constitute a door 2, the forward upper transverse margin of which is hinged at 4 to the rear extremity of the upper fixed wall 3 of the fuselage. Within the fixed lower wall 5 of the fuselage a rigid 35 flooring 15 is provided which forms the floor of the storage space, and may extend rearwardly of the hinges 4 as shown at 16, in which case the lower movable wall portion 7, forming a portion of the door 2, is made shorter than the movable upper wall portion attached thereto.

The airplane, when on the ground, is supported upon suitable landing gear 11, and adjacent the rear of the fixed portion of the fuselage tail 40 wheels 6 may be provided.

45 The latter are preferably retractably mounted so that when desired the rear fixed portion of the fuselage may rest directly upon the ground. The rearwardly projecting portion 16 of the flooring 15 may also be hingedly connected to the 50 latter to form a ramp if desired as shown at 16a.

In order that the rear controls, rudders and the like, generally designated by the numerals 19, 55 may be positioned to permit both unimpeded movement of the hinged rear fuselage portion

or door 2, and also to provide easy access through the doorway 8 formed when the said door is open, or in raised position, shown in Figure 2, rigid rearward extensions 10 of the fuselage sides are provided which are upwardly directed at their rear extremities, and upon which the said rear controls are appropriately mounted.

18 denotes props or supports which may also be provided to extend between the nose of the fuselage and the ground to prevent tipping of the airplane in a forward direction when heavy loads are being moved adjacent the front of the storage space.

From the foregoing it will be clearly seen that I have devised a simple form of construction wherein a doorway is located adjacent the rear of the fuselage quite close to the ground to permit easy and rapid loading across the entire width of the fuselage. Again the rearward extensions of the fuselage sides provide satisfactory supporting means for the rear controls so positioned that ample headroom is afforded during loading operations and ample clearance is furnished for movement of the door. Again the operating rods (not shown) for the tail controls may be easily arranged so that they are in no wise affected by the opening of the door.

It is also understood that the invention is susceptible to such alterations and modifications as fall within the scope of the appended claims.

What I claim is:

1. In an airplane the combination of a fuselage the rear end of which is adapted to rest near or upon the ground when the plane is grounded, a storage space in said fuselage extending forwardly from the rear thereof, and a load-supporting floor arranged within said storage space in spaced relation to the bottom of the fuselage wall, said floor including a rearmost portion pivotally connected to the main floor whereby the same may be lowered to form a ramp, the wall at the extreme rear of said fuselage including a portion between the side walls displaceable with reference to the main fuselage wall to thereby form an opening for loading and unloading said storage space.

2. In an airplane the combination of a fuselage the rear end of which is adapted to rest near or upon the ground when the plane is grounded, a storage space in said fuselage extending forwardly from the rear thereof, a load-supporting floor arranged within said storage space in spaced relation to the bottom of the fuselage wall, said floor including a rearmost portion pivotally connected to the main floor whereby the same may be lowered to form a ramp, the wall at the extreme rear of said fuselage including a portion between the side walls displaceable with reference to the main fuselage wall to thereby form an opening for loading and unloading said storage space, and a tail wheel retractably mounted between the bottom of the fuselage wall and the load-supporting floor adjacent the rear end of said latter.

3. An airplane fuselage the rear end of which is adapted for support upon or near the ground at a point forwardly of its extreme rear when the plane is grounded, and including storage space extending forwardly from the rear thereof, said fuselage comprising a top wall and a bottom wall curving upwardly from adjacent and rearwardly of the point of rear end support to meet the top

wall, side walls laterally spaced and conforming in contour at their rear ends to the margins of the top and bottom walls, a portion of the top and bottom walls extending forwardly from the extreme rear being disconnected from the side walls for movement together as a unit, the bottom wall portion of said movable unit terminating along a substantially transverse line between the fuselage rear end support and the rear end of the fuselage, and the top wall portion terminating in a substantially transverse line forwardly of the terminating line of the bottom wall portion and being pivotally connected to the adjacent fixed portion of the top wall.

4. In an airplane the combination of a fuselage the rear end of which is adapted for support upon or near the ground at a point forwardly of its extreme rear when the plane is grounded, and including storage space extending forwardly from the rear thereof, said fuselage comprising a top wall and a bottom wall curving upwardly from adjacent and rearwardly of the point of rear end support to meet the top wall, side walls laterally spaced and conforming in contour at their rear ends to the margins of the top and bottom walls, a portion of the top and bottom walls extending forwardly from the extreme rear being disconnected from the side walls for movement together as a unit, the bottom wall portion of said movable unit terminating along a substantially transverse line between the fuselage rear end support and the rear end of the fuselage, and the top wall portion terminating in a substantially transverse line forwardly of the terminating line of the bottom wall portion and being pivotally connected to the adjacent fixed portion of the top wall, and a load-supporting floor arranged within said storage space and extending rearwardly of said pivotal connection, said floor being spaced from the bottom of the fuselage wall.

5. In an airplane the combination of a fuselage the rear end of which is adapted for support upon or near the ground at a point forwardly of its extreme rear when the plane is grounded, and including storage space extending forwardly from the rear thereof, said fuselage comprising a top wall and a bottom wall curving upwardly from adjacent and rearwardly of the point of rear end support to meet the top wall, side walls laterally spaced and conforming in contour at their rear ends to the margins of the top and bottom walls, a portion of the top and bottom walls extending forwardly from the extreme rear being disconnected from the side walls for movement together as a unit, the bottom wall portion of said movable unit terminating along a substantially transverse line between the fuselage rear end support and the rear end of the fuselage, and the top wall portion terminating in a substantially transverse line forwardly of the terminating line of the bottom wall portion and being pivotally connected to the adjacent fixed portion of the top wall, a load-supporting floor arranged within said storage space and extending rearwardly of said pivotal connection, said floor being spaced from the bottom of the fuselage wall, and a tail wheel retractably mounted between the bottom of the fuselage wall and the load-supporting floor adjacent the rear end of the latter.
